attorneys

UNITED STATES PATENT OFFICE.

PAUL W. FLEISCHER, OF WEEHAWKEN HEIGHTS, NEW JERSEY, ASSIGNOR TO AMERICAN CAN COMPANY, OF NEW YORK, N. Y., A CORPORATION OF NEW JERSEY.

FEEDING AND SPACING MECHANISM FOR FILLED-CAN-CLOSING MACHINES.

Original application filed November 28, 1913, Serial No. 803,406, Patent No. 1,406,631, dated February 14, 1922. Divided and this application filed January 9, 1922. Serial No. 528,028.

This invention relates in general to can closing machines and has more particular reference to devices in such machines for properly spacing and timing the cans in their movement to the seaming mechanism, the present application being a division of my application Serial Number 803,406, filed November 28, 1913, now granted Feb. 14, 1922, Patent No. 1,406,631.

10 A principal object of the invention is the provision of means for automatically separating and arranging the cans in desired relationship during their movement upon a rotatable feeding turret.

15 Numerous other objects and advantages of the invention will be apparent as it is better understood from the following description, which, taken in connection with the accompanying drawings, discloses a preferred embodiment thereof.

Referring to the drawings,

Figure 1 is a plan view of that portion of a can closing machine in which my invention is embodied; and

25 Fig. 2 is a partial horizontal section taken through the bed plate upon which the parts of the machine shown in Fig. 1 are supported, and showing the gearing by which the operating parts are driven.

30 Upon the drawings I have shown a rotatable table 33 and two stationary tables 34 and 35 over which the cans are fed in their travel to the closing or seaming mechanism (not shown). It will be understood that the entire structure is supported upon a suitable base and is arranged about a vertical cylindrical standard 36 and a sleeve 58 shown in section in Fig. 1.

The cans are placed in any suitable manner upon the rotary table 33 and are guided between a detachable arcuate guard 46 and a central disk 48 which latter is rotatable in unison with the table 33. The disk 48 is provided with a plurality of equally spaced projections 49 about its periphery and the guard 46, which is removably secured to the fixed frame by bolts 41, has mounted therein a desired number of yielding spring plates 47, two being shown in the present instance.

45 As the cans crowd one upon the other while being fed by the table 33 they are frictionally engaged by the yieldable members 47 and moved thereon by the projections 49 until

they are individually forced into recesses 42 between said projections and thereby spaced a uniform distance apart and delivered in properly spaced and timed relationship to a rotatable star wheel 50 located above the table 34. The cans are indicated in outline by the reference character 43 and are directed by said star wheel 50 about the table 34, being guided by an arcuate guard 51 removably secured to said table by bolts 44. The cans are then directed into a guideway 60 where they are engaged by propelling arms or flights 66, which are mounted for rotation above the table 35 and which move said cans to the assembling and seaming stations. A lever 89 pivoted at 90 extends into the guideway 60 and is a part of a device for controlling the feeding of can ends so that no end is fed unless a can is in position to receive it.

The means by which the rotatable members heretofore referred to are driven may be understood by reference to Fig. 2. Power from a suitable source of supply (not shown) is transmitted to a gear 71 secured upon a vertical shaft 70 which carries also a pinion 72 meshing with a gear 73 upon a shaft 74 by which the flights 66 are operated, said gear 73 meshing also with a gear 75 carried upon the lower end of a shaft 54 to which is fixedly secured the star wheel 50. A gear 76 is driven by the gear 75 and rotates a shaft 77 carrying at its upper end the rotatable table 33. Said gearing is contained within a box or bed plate 32 and is so arranged that the various operating parts are moved in properly timed relationship.

A top plate 78 is provided to hold the disk 48 in place, and it will be understood that said disk is rotated by the shaft 77 in unison with the table 33.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for securing can ends to

can bodies, a rotatable feeding member having thereon a plurality of can-engaging and spacing elements, and a relatively stationary outer can-engaging member serving as a can body guide and arranged substantially concentric with the path of said spacing elements, one of said parts being yieldable radially to permit the can to roll over said spacing elements and into a space therebetween while rolling against said outer member.

2. In a machine for securing can ends to can bodies, a rotatable feeding member having thereon a plurality of can-engaging and spacing elements, and a relatively stationary outer can-engaging member serving as a can body guide and arranged substantially concentric with the path of said spacing elements, said outer member having parts yieldable under the pressure of a can permitting the latter to roll over said spacing elements and into a space therebetween while rolling against said outer member.

3. A conveying apparatus for articles including in combination, traveling timing and delivering means having spacing projections, yielding pressure means adapted to place each article in position to be conveyed by said timing and delivering means and means for advancing articles into engagement with and along said pressure means, the yielding pressure means being spaced from said projections so that an article can pass over said projections while acted on by the said pressure means.

4. A conveying apparatus for delivering filled cans to a closing machine including in combination, traveling timing and delivering means having spacing projections, pressure means comprising a plurality of yielding members adapted to place said cans in position to be conveyed by said traveling means and means for advancing cans into engagement with and along the pressure means, the yielding pressure means being spaced from said projections so that an article can pass over said projections while acted on by the said pressure means.

5. A conveying and timing apparatus for delivering filled cans to a closing machine including in combination, traveling timing fingers, a support adapted to receive the filled cans promiscuously, and means cooperating therewith for placing the cans against the timing fingers, said means including a plurality of yielding members arranged successively, said yielding members being opposed to the traveling timing fingers for forcing the cans into proper relation therewith.

6. A conveying and timing apparatus for delivering filled cans to a closing machine including in combination, traveling timing fingers, a support adapted to receive the filled cans promiscuously, and means co-

operating therewith for placing the cans against the timing fingers, said means including a plurality of yielding members, said yielding members being opposed to the traveling timing fingers for forcing the cans into proper relation therewith, said yielding members being so constructed that the cans pass from one to another of said members.

7. A conveying and timing apparatus for articles, comprising means having a moving bottom support for advancing said articles, means for spacing and timing said articles and means cooperating with said spacing and timing means for disposing said articles in proper traveling position.

8. A conveying and timing apparatus for delivering articles to a station to be operated upon, comprising a moving pathway having a moving supporting bottom, means traveling in unison with said pathway for spacing and timing said articles, and means cooperating with said spacing and timing means for disposing an article between two of said spacing and timing means.

9. A conveying apparatus for articles, comprising a traveling support having a moving supporting bottom, timing means engaging opposite surfaces of the articles conveyed, one of said means having spaced projections, the other of said means including yielding devices to force the articles into timed position between successive projections of the other means.

10. A conveying apparatus for articles, comprising a traveling support having a moving supporting bottom for advancing the articles through the apparatus, timing means for engaging the articles so advanced and a spring element for forcing said articles into engagement with the timing means, whereby the articles are partially rotated about the timing means into correct traveling position.

11. A conveying and timing apparatus for articles, comprising means for advancing said articles, means comprising yielding elements for spacing and timing said articles and means cooperating with said spacing and timing means for retarding said articles and arranging them in proper traveling order.

12. A conveying apparatus for articles including in combination traveling timing and delivering means, yielding pressure means adapted to place each article in position to be conveyed by said timing and delivering means and means for advancing articles into engagement with and along said pressure means.

13. A conveying apparatus for delivering filled cans to a closing machine including in combination, traveling timing and delivering means, pressure means comprising a plurality of yielding members adapted to place said cans in position to be conveyed by said

traveling means and means for advancing cans into engagement with and along the pressure means.

14. A conveying and timing apparatus for delivering filled cans to a closing machine including in combination, traveling timing fingers, a rotatable support adapted to receive the filled cans promiscuously, and

means cooperating therewith for placing the cans against the timing fingers, said means including a plurality of yielding members arranged side by side, said yielding members being opposed to the traveling timing fingers for forcing the same into proper relation therewith.

PAUL W. FLEISCHER.
